PROCESSING HYDROCARBON OILS

Joseph K. Roberts, Flossmoor, and Jay H. Forrester and Roy J. Diwoky, Chicago, Ill., assignors to Standard Oil Company, Chicago, Ill., a corporation of Indiana

Application May 29, 1937, Serial No. 145,468

3 Claims. (Cl. 196—48)

This invention relates to the treating of hydrocarbon oils and particularly to the cracking of higher boiling petroleum oils for the production of gasoline, kerosene, furnace oil and other low boiling distillates. One of the objects of the invention is to convert heavy oils such as gas oil into gasoline and furnace oil by simultaneously withdrawing these products from different parts of the cracking unit. Another object of the invention is to remove unstable hydrocarbons such as propane, from the gasoline and furnace oil fractions with a minimum cost for fuel and equipment. Still another object of the invention is to improve the operation of the cracking unit by a novel means of control wherein the charging rate to the unit is maintained constant. Still another object of the invention is to operate two or more cracking units in unison connected to a common furnace oil stabilizer where the furnace oil fraction is distilled by its contained heat to remove undesirable gases. The furnace oil containing gasoline constituents may then be subjected to chemical treatment and redistilled to produce the desired boiling range and obtain at the same time a chemically treated gasoline fraction which may be blended for the production of a special grade of gasoline. Other objects of the invention will be apparent from the following description.

The drawings which form a part of this specification show diagrammatically an arrangement of two or more cracking units coupled in parallel with separate common discharge lines for gas, gasoline, furnace oil and tar and with combined stabilizing equipment for furnace oil and gasoline. Figure 2 is an extension of the diagram shown in Figure 1. The invention will be readily understood by reference to the drawings and the following description thereof.

Referring to the drawings, A and B are members of a series of cracking units, A, B, C, D, etc., only two of which are shown. The cracking units are connected by furnace oil header line 10 and gasoline header 11 to furnace oil stabilizer 12 and gasoline debutanizer 13 respectively. A stabilizing column 14 is provided to remove undesirable propane and other fixed gases from the gasoline and light constituents obtained as a distillate from the furnace oil stabilizer and the debutanizer. Tar flash drum 15 is provided to receive the hot tar from all the cracking units and distil it by contained heat, thereby removing gasoline and other lighter fractions. The gasoline containing distillate removed from the tar may be returned as reflux to the fractionat-

ing towers of the cracking units A, B, etc., through reflux header 16.

In conducting the operation we prefer to charge Mid-Continent gas oil having about the following boiling range:

	° F.
Initial	290
50%	652
65%	700
81%	750 10

This stock, hereinafter called fresh feed, is introduced through header 17 by pumps not shown. From the header 17 the fresh feed is withdrawn through line 18 and reflux exchanger 19 to line 20 leading to cracking coils 21 and 22, in furnace 23. If desired, a portion of the fresh feed may be directed through line 24 into the top of the evaporator 25 to serve as reflux therein. A portion may also be withdrawn through line 26 directly into vapor line 27 for the purpose of cooling and fluxing this line and preventing formation of coke therein.

At the point of entering coil 22 in furnace 23 the fresh feed may be commingled with recycle stock withdrawn from fractionator 28 by line 28a as hereinafter described. The combined fresh feed and recycle oil in passing through furnace 23 is heated to a higher temperature in the range of 900-1000° F. where it is substantially all vaporized. The hot vapors are conducted by transfer line 29 to soaking drum 30 and thence by line 31 to evaporator 25. A considerable proportion of the oil is converted to lower boiling hydrocarbons in the furnace 23 and in soaking drum 30. The pressure in the soaking drum may suitably be from 100 to 400 lbs. per sq. in. under which conditions the oil will be substantially all in the vapor phase. The hot vapors are partially condensed by reflux cooling in evaporator 25 and a heavy tar fraction is withdrawn therefrom by tar drag line 32 connected to tar header 33.

The vapors in evaporator 25 are conducted by line 27 to fractionator 28 where they are further cooled and fractionated to remove the gasoline constituents and an intermediate fraction herein called "furnace oil distillat.". Gasoline vapors are withdrawn from the fractionator by vapor line 34 leading to condenser 35 where all the gasoline is condensed and conducted with separated gases to separating drum 36. Vent 37 connects the separating drum to the dry gas header 38 and distillate discharge line 39 similarly conducts the gasoline from separator 36 to distillate header 11. The gas discharged into

header 38 may be substantially free from gasoline, in which case it is discharged from the system to be used as fuel gas or burned in the furnaces, A, B, etc. The pressure in the fractionator 28 may be approximately the same as that in the soaking drum 30 and evaporator 25. If desired, however, the pressure may be reduced in the evaporator 25 and/or the fractionator 28 by placing valves in lines 31 and 27. Thus a pressure of 50 to 100 lbs. may be conveniently maintained in evaporator 25 and/or fractionator 28.

As the hot vapors ascend fractionator 28 they are cooled by reflux from reflux exchanger 19 and also from reflux line 40 connected to reflux header 16. As a result of the cooling heavy uncracked constituents together with partially cracked constituents of the gas oil originally charged are condensed and recycled from the bottom of the fractionator as previously described. An intermediate boiling fraction is collected on plates 41 of the fractionator whence it is withdrawn from furnace oil trap-out line 42 connected to header 10. The amount of furnace oil distillate removed in this way is controlled by valves 44 and 45, the withdrawal being regulated to maintain a relatively constant liquid level in the base of the fractionating tower 28. In operating our process we prefer to maintain a constant rate of feed through lines 20 and 28a which may be accomplished by keeping the operation of the fresh feed pump (not shown) and the recycle pump 46 substantially constant. Any variation in the extent of cracking due to change in temperatures, nature of feed stock, and other conditions may be compensated for by withdrawing a greater or lesser amount of furnace oil stock from the mid-portion of fractionator 28. As a result much more uniform operation of the cracking unit is obtainable and higher through-put results. Uniform charge to furnace 23 also facilitates the control of combustion in the furnace to give uniform outlet temperature. Thus in comparison with control of the operation of the unit by the usual means of regulating the amount of feed stock, the charging capacity of the unit was increased from 140 bbls. per hr. to 150 bbls. per hr. when using our new method of cracking unit control. When operating with a fresh feed rate of 150 bbl./hr. the furnace oil distillate withdrawal may be about 20-50 bbl./hr. or 30 bbl./hr. in a typical instance. At the same time, the gasoline production from the top of tower 28 may be about 52 bbl./hr. and the furnace oil distillate may contain an additional 35% of gasoline.

55 The furnace oil stream collected by header 10 is conducted by line 47 to furnace oil stabilizer 12 where it is introduced at a temperature of about 580°-600° F. The pressure is reduced by valve 48 to about 90 lbs./sq. in., thus causing the evaporation of a light gasoline and gas fraction, the vapors being withdrawn by line 49 through cooler 50 and thence to accumulator drum 51. Reflux condensate may be returned to the stabilizer 12 by reflux line 52. The stabilized furnace oil distillate is withdrawn from the base of stabilizer 12 by line 53 leading to cooler 54 and furnace oil distillate tank 55. This stock may have the following distillation range:

	° F.
Initial	270
20%	377
50%	429
Maximum	576

75 Gasoline distillate withdrawn from the base of

the separator 36 by line 39 to distillate header 11 is conducted by line 56 to feed tank 57 whence it is led by line 58 through heater 54 into debutanizer column 13. In the column 13 there is removed from the gasoline distillate most of the butane, together with some pentane and heavier constituents and substantially all propane and lighter hydrocarbons at a pressure of about 50 to 125 lbs. per square inch. Vapors of these light hydrocarbons are conducted by line 59 through condenser 60 and into reflux accumulator 51 whence sufficient condensate is withdrawn by lines 52 and 61 to supply the desired reflux in column 13. Uncondensed gases are withdrawn from accumulator 51 by line 62 leading to condenser 63 and stabilizer feed tank 64. Uncondensed vapors are withdrawn from tank 64 by line 65, and combined with vapors from feed tank 57 discharged by line 66. The combined vapors are conducted to absorber 67 where some propane and substantially all the butane and heavier gasoline hydrocarbons are recovered in an absorber oil introduced by line 68 and discharged to a suitable gasoline recovery system by line 69. The unabsorbed gases are discharged by line 70 leading to fuel gas header 38.

Liquid butane and other light hydrocarbons condensed in tank 64 are withdrawn by line 71 leading to stabilizer 14 where propane and lighter hydrocarbons are separated under pressure from butane and heavier desired gasoline constituents. The pressure in 14 may be about 150 to 350 lbs. per sq. inch. The vapors are conducted from stabilizer 14 through a suitable reflux exchanger 72 and reflux drum 73 whence the uncondensed vapors are discharged to the fuel line by line 74. Reflux is supplied to the stabilizer 14 by line 75.

Heat for operating stabilizer tower 14 is supplied by heater 76 through which is circulated liquid trapped from the tower by line 77 and returned thereto by line 78. Stabilized liquid is withdrawn from tower 14 by line 79 and conducted to storage tank 80.

The debutanizer column 13 may be supplied with heat from heater 81 in a manner similar to that employed for heating stabilizer 14. Heat for heaters 76 and 81 may be conveniently obtained by circulating a stream of hot tar therethrough. Hot furnace oil distillate from header 10 may likewise be used for this purpose or we may also use recycle gas oil from tower 88.

Debutanized gasoline from the base of tower 13 is withdrawn by line 82 through cooler 83 and thence by line 84 to debutanized gasoline storage tank 85. This gasoline distillate is substantially free from heavier hydrocarbons boiling above the gasoline range. For example, it may have a boiling range as indicated by the following A. S. T. M. distillation:

	° F.
Initial	143
50%	260
90%	339
Maximum	397 65

It may be withdrawn from receiver 85 by line 100 and sweetened by treating with sodium plumbite or other sweetening reagent in plant 101 (Figure 2) to remove malodorous sulfurous compounds and thereafter it may be treated with 70 an antioxidant to prevent gum formation in subsequent storage and handling. From sweetening plant 101 the gasoline may go by line 102 to storage in tank 103. No chemical refining with sulfuric acid is necessary nor is it necessary to 75

subject this distillate to redistillation before blending to make finished motor fuel. To obtain gum stability we may add about .002% to .005% of monobenzyl aminophenol or other suitable gasoline antioxidant.

5 Hot tar which is withdrawn from evaporator 25 and the other evaporators of the cracking units A, B, etc. is conducted through tar lines 32, tar header 33 and line 86 to tar flash tower 15 where it is distilled by its contained heat and the vapors are conducted by line 87 to fractionator 88 where it may be divided into several fractions as desired. The light distillate from fractionator 88 may be conducted by line 89 to condenser 90 and separator 91 whence the liquid is withdrawn by line 92 to reflux accumulator 93. Here it may be blended with other light distillate introduced by line 94 and the mixture is then conducted by line 95 to reflux header 16. By operating in this way the gasoline constituents of the tar find their way back to the fractionating column 28 and also light constituents of the tar which are desired in the furnace oil find their way to the furnace oil stream withdrawn from the fractionating tower by line 42. Unvaporized constituents of the tar are withdrawn from flash tower 15 by line 96 and may be treated to produce satisfactory heavy fuel oil, for example by hot filtration or other suitable method of treatment. Additional tar distillate fractions may be withdrawn from suitable trap-out plates not shown and from the base of fractionator 88 by line 97 as desired.

35 Stabilized furnace oil distillate collected in receiver 55 may be withdrawn by line 104 and treated with sulfuric acid in the usual manner in plant 105 and redistilled in 106 to produce stable light and heavy gasoline fractions and a furnace oil fraction. A tractor fuel fraction may also be separated. These may have about the following 40 distillations:

	Light gasoline	Heavy gasoline	Tractor fuel	Furnace oil
45 Initial.....	° F. 112	° F. 250	° F. 358	358
50 percent.....	242	385	423	452
60 percent.....	318	382	471	489
Maximum.....	374	420	512	550

50 The acid treatment of the furnace oil distillate may be controlled to give a gasoline fraction on subsequent distillation which will have any desired light color, lighter than the color of the untreated gasoline obtained in receiver 85. For example, when applying about 2 lbs. of 80% H₂SO₄ per barrel, the color of the gasoline fraction from treated furnace oil distillate may be 25 Saybolt whereas the color of the gasoline in receiver 85 may be 20 Saybolt. The gasoline fraction from furnace oil distillate may likewise require no antioxidant for gum stabilization.

65 The stabilized light gasoline and heavy gasoline in receivers 80 and 85 may be blended by line 107 in proper proportion to produce a motor fuel having the desired volatility. For example, 30 volumes of stabilized light gasoline may be blended with 70 volumes of stabilized heavy gasoline to produce a motor fuel having a Reid vapor pressure of 11.8 pounds and a volatility indicated by the percent distilled at 158° F. of 24.3%. The composition of the stabilized light gasoline in tank 80 may be varied, depending on the conditions of operating debutanizer 13. Thus, by operating debutanizer 13 at a higher temperature

more light gasoline will be produced having a lower volatility.

One of the advantages of our process is the unified stabilization system for both gasoline and furnace oil distillates represented by towers 12, 13 and 14. The operation of unit stabilization of this character is made possible by the manifolding of a large number of cracking units, for example 5 or 10 units, thus providing a relatively constant supply and composition of feed stocks for the unit stabilization system even when one or more of the units are shut down temporarily for cleaning. Another advantage of our process which has been mentioned hereinbefore is the improved control of the cracking operation by trapping out of the fractionator a variable amount of furnace oil distillate which would otherwise be recycled in the unit. Regulation of the cracking unit by regulating the withdrawal of furnace oil distillate from the fractionator controls the balance between the furnace, evaporator, the fresh feed charging stock, the recycle stock and the fractionator. The result is a smoother operation than has been heretofore obtainable.

25 Still another advantage of the process is the return of light distillate from the tar to the cracking unit fractionators as reflux where heavier portions are fractionated and withdrawn with the furnace oil distillate stream without any further cracking or imposing any additional duty on the cracking coil.

To still further aid in balancing the operation of the cracking units and maintain desired inventories of refinery stocks, a part, or at times, 35 all of the furnace oil may be blended with the charging stock to the units. This, however, results in making the stock somewhat more refractory, since elimination of the furnace oil results in increasing the paraffinicity of the charge to the 40 coils and thereby increases gasoline producing capacity.

Although we have described our invention by means of specific examples, we intend it to be limited only by the following claims.

45 We claim:

1. In the process of converting heavy hydrocarbon oils into gasoline and an intermediate boiling furnace oil fraction wherein the heavy hydrocarbon oil is subjected to cracking in a cracking zone and the products are separated from tar in an evaporating zone and thereafter fractionated under pressure in a fractionating zone from which gasoline vapor is withdrawn at the top, incompletely cracked hydrocarbons are condensed and withdrawn at the bottom whence they are recycled to said cracking zone, and an intermediate boiling furnace oil condensate containing dissolved gasoline is withdrawn from an intermediate point of said fractionating zone, the improvement comprising conducting said furnace oil condensate to a second fractionating zone at lower pressure where dissolved gasoline is separated from the furnace oil fraction, withdrawing and condensing gasoline vapors from the fractionating zone first mentioned and separating uncondensable gases therefrom, conducting the gasoline condensate to a third fractionating zone and separating substantially all the propane therefrom together with some butane and higher hydrocarbons, condensing the separated propane fraction and combining it with the gasoline fraction removed from said furnace oil distillate separated in said second fractionating zone, conducting said combined gasoline and propane frac-

tion to a fourth fractionating zone maintained at higher pressure than the second and third fractionating zones, and separating substantially all propane and lighter hydrocarbons from butane and heavier hydrocarbons in said fourth fractionating zone.

2. The process of claim 1 wherein the gasoline residue in said third fractionating zone, which is substantially free from propane, is combined with the residue in said fourth fractionating zone also substantially free from propane to produce a suitable stabilized motor fuel product.

3. The process of obtaining uniform operation in a battery of cracking units wherein each unit is supplied from common headers with fresh feed stock, fuel and fractionating tower reflux and each unit is likewise arranged to discharge gasoline distillate, gas, furnace oil condensate and tar into other suitable common headers, and 20 wherein one or more units is periodically shut

down temporarily for cleaning while the remaining units continue operating, comprising combining furnace oil condensate from all operating units and distilling gases and dissolved gasoline therefrom in a first single fractionating zone by the contained heat of said condensate, combining gasoline distillates from all units and distilling therefrom a light fraction including all the propane in a second single fractionating zone, combining the overhead fractions thus obtained from said first and second fractionating zones and subjecting them to further fractionation under pressure to separate gasoline from propane and lighter hydrocarbons, and regulating the rate of withdrawing furnace oil condensate from each unit 15 to maintain a constant rate of fresh feed charged thereto.
